UNITED STATES PATENT OFFICE.

ROBERT S. CURLEY, OF LOWELL, MASSACHUSETTS, ASSIGNOR, BY MESNE ASSIGNMENTS, TO KITSON MACHINE SHOP, A CORPORATION OF MASSACHUSETTS.

CONDENSER.

Application filed September 28, 1925. Serial No. 58,779.

This invention relates to condensers of the character used in textile mills.

It is the usual practice in such mills to convey cotton or other fibre in a stream of air and a condenser is used at any point in the system where it is desired to deposit the fibre, or, in other words, to separate it from the current of air in which it is carried. Such a condenser usually comprises a rotary screen mounted in a casing and revolved slowly. A suction fan creates the current or air which carries the cotton to the condenser and draws this air through the screen. A shield covers the inner surface of a part of the screen and relieves the suction at that point so that the fibre will fall off the screen as successive portions of the screen pass over the shield.

Considerable trouble has been experienced in prior condensers with air leakage, particularly around the ends of the screen, such leakage tending to pack the fibre into the clearance space between the ends of the screen and the casing and thus to introduce very serious frictional resistance to the rotation of the screen. There is always a tendency, also, for dust to accumulate around the ends and bearings of the screen, and such accumulations later become dislodged and are carried into the fibre by the air leakage currents. This ultimately results in producing blemished goods. Furthermore, as the condenser becomes worn the air leakage becomes a more troublesome factor.

The present invention is especially concerned with the conditions above described, and it aims to improve the construction of condensers with a view to controlling the air leakage more effectually throughout the life of the condenser, preventing the accumulation of dirt and foreign material where it may subsequently be dislodged and become mingled with the fibre, facilitating the manufacture and maintenance of the machine, and particularly to preventing the packing of the fibre into the clearance spaces at the ends of the screen.

The nature of the invention will be readily understood from the following description when read in connection with the accompanying drawings, and the novel features will be particularly pointed out in the appended claims.

In the drawings, Figure 1 is a perspective view of a condenser constructed in accordance with this invention;

Fig. 2 is a perspective view of the end of the condenser opposite to that shown in Fig. 1;

Fig. 3 is a vertical, transverse, cross-sectional view of the condenser shown in Figs. 1 and 2; and

Fig. 4 is a horizontal cross sectional view on substantially the line 4—4, Fig. 3.

The machine shown comprises a cylindrical screen 2 partly enclosed in a casing 4. The screening surface may consist of wire fabric, a perforated sheet metal plate, or the like, and the screen includes flanged rings 6—6 at the opposite ends thereof which support the screening surface. Preferably these flanged rings are of channel section, as shown in Fig. 4. Each ring is supported by a series of rolls 7, Figs. 3 and 4, which are mounted on axles 8 supported in the end plates of the casing 4. The rolls engage the flanges of the annular members 6—6 and thus support the screen for free rotation in the casing with the edge of each flange fitting against the inner surface of its respective end plate of the casing, a sufficient clearance only being provided between the flanges and the end plates to permit the screen to run freely.

In order to rotate the screen 2, the inner flange 10 of each of the end rings 6—6 is toothed to mesh with a pinion, as shown at 12 in Fig. 3, both of these pinions mounted on a shaft 13. This shaft carries a gear 14 which is driven by a pinion 15 on another shaft 16. A pulley 17, Fig. 2, is secured on the latter shaft and may be belted to any convenient source of power.

An inlet 20, Figs. 1 and 3, is provided in the casing at one side thereof for the admission of the fibre laden current of air. This current of air, as in prior constructions, is created by a suction blower or fan which is connected to the discharge end of the condenser. The air passes through the screen 2 into the interior thereof and then flows into a conduit or air pipe 21 which extends through both the screen and one end of the casing 4. The conduit 21 is located co-axially with the screen 2 and its inner end is abutted against and closed by one of the end plates of the casing, as clearly shown in Fig. 4. A long tapered opening 22, Fig. 4, is formed in the upper side of this conduit, the opening being relatively narrow at the discharge end of the conduit but increasing gradually in width toward the closed end thereof. This construction results in distributing the air flow more uniformly over the entire length of the screen, the increase in width of the opening 22 compensating for the increase in air resistance toward the closed end of the conduit.

One or more air holes 24 are formed through each end plate of the casing where they open into the channel sections in the end rings 6-6 of the screen. As shown, two of these air holes are provided through each end plate. Air thus can flow freely into the channel spaces in the end rings and a small part of this air can leak around the edges of the flanges of the rings through the clearance spaces provided between these flanges and the end plates. The air leakage produced in this manner is a relatively constant quantity so that suitable allowance can be made for it in the design of the machine. It has the advantage both of preventing dirt and dust from accumulating in those portions of the screen where such accumulations otherwise would form, and later would be dislodged and become mingled with the fibre but more especially of preventing inward leakage currents around the ends of the screen where they cause fibre to pack into the clearance space between the rings and the casing.

Preferably the end plates of the casing 4 each includes a removable section 58, Figs. 1 and 2, which is bolted to the main body of the casing and carries the axles which support the rolls 7. This construction facilitates the manufacture and assembly of the parts, and also is of advantage in case repairs become necessary.

In order to prevent the reverse movement of air through the screen, or in other words, to close the space between the conduit 21 and the screen 2, damper plates 25 and 26, Figs. 3 and 4, are provided at the opposite sides of the conduit. The plate 25 has flanges at its opposite ends, one of these flanges being

shown at 27, Fig. 3, and each flange bears against the inner surface of one of the end plates of the casing and is slotted to receive bolts 28 by means of which the damper plate is adjustably secured in its operative position. A narrow flap 29 of leather, felt, or the like, is secured to the outer edge of the plate 25 and bears against the inner surface of the screen 2. This plate, therefore, substantially closes the space between the conduit and the screen at one side of the conduit. The damper plate 26 is similarly secured in place by bolts 30, Fig. 3, and it has a flap 31 at its outer edge to bear against the inner surface of the screen. Another plate 32 is formed integral with, or is secured to the lower part of, the wall of the intake opening 20 and projects inwardly, a flexible flap 33 being secured to its inner edge to bear against the outer surface of the screen, preferably at a point opposite to the flap 29. This relationship is clearly shown in Fig. 3. These damper plates 25, 26 and 32 prevent any substantial leakage of air into the suction side of the condenser.

When the machine is in operation the cotton, wool, hair, or other fibre carried by the current of air entering the intake opening 20 is deposited on the surface of the screen 2 as the air flows through this screen, and this fibre is carried around with the screen as it rotates slowly. As the fibre passes the damper plate 26, the suction holding it on the screen is relieved, and the fibre is removed from the screen immediately after it has passed the damper plate. In order to facilitate this removal upper and lower rolls 35 and 36 are provided at the discharge side of the condenser. The upper roll 35 is mounted on a shaft 37 which is supported in two arms 38 and 39, respectively, both pivoted above and at one side of the roll 35 so that the weight of the roll 35 tends to hold it against the surface of the screen 2. This roll thus presses the fibre carried by the screen against the screen surface. The roll 35 is rotated by a gear 40 mounted on the end of the shaft 37 and running in mesh with another gear 41 which is driven by the gear 14 previously referred to. A link 47 connects the axles of the gears 40 and 41, while another link 48 connects the axle of the latter gear with the shaft 3 on which the gear 14 is mounted. These links hold the gears in mesh with each other while the roll 35 swings outwardly more or less due to the fibre passing between it and the screen.

For the purpose of closing the space between the press roll 35 and the casing 4, the bar 42, Fig. 3, is mounted rigidly on the arms 38 and 39, and an angle plate 43 is secured to this bar and holds a flap 44 of leather, or other flexible material, pressed against the outer surface of the roll 35.

Another flap 45, Fig. 3, is secured along the edge of the opening in the casing and bears against the angle plate 43.

The rolls 35 and 36 rotate toward each other, the stripper roll 36 acting to peel the layer of fibre off the screen 2, and the two rolls cooperate to feed this layer of fibre out between them and away from the screen. It is desirable that this fibre shall not be in a compact sheet but shall be kept in a loose and fluffy condition. For this purpose the rolls are driven at different peripheral speeds. As shown, the lower roll 36, which is mounted on the shaft 16, is driven at a higher speed than the upper roll 35, the desired difference in speed being obtained through the gear connections between the shafts 16 and 37.

It will now be appreciated that this invention provides a condenser construction in which accumulations of dirt or fibre are effectually prevented from forming in the machine. Aside from the damage which such accumulations may cause in the work produced by the machine, they are also extremely dangerous since they may so increase the friction generated in the machine as to cause fire or even to break the machine. The elimination of inward leakage currents around the ends of the screen also is of advantage in permitting the fibre to drop off the screen freely after it has passed the damper plate 26. The mounting of the condenser screen is such that the air leakage is substantially constant and is not greatly affected by wear, as in prior types of condensers.

While I have herein shown and described the best embodiment of my invention that I have so far devised, it will be evident that this embodiment may be modified in many particulars without departing from the spirit or scope of the invention.

Having thus described my invention what I desire to claim as new is:

1. In a condenser, the combination of a rotary screen, a casing in which said screen is partly enclosed, said casing having an inlet opening in one side thereof, a stationary air conduit within said screen arranged to receive the air flowing through the screen and discharge it from the condenser, and stationary dampers between said screen and conduit and between said casing and screen.
2. In a condenser, the combination of a rotary cylindrical screen, a casing in which said screen is partly enclosed, said casing having an inlet opening in one side thereof, a stationary air conduit within said screen extending longitudinally of the screen for receiving the air flowing through the screen and discharging it from the condenser, a stationary damper plate extending from one side of said conduit to a point closely adjacent to the screen and substantially closing

the space between said screen and conduit at one side of the conduit, and a flexible flap secured to the edge of said damper plate and bearing against said screen.

3. In a condenser, the combination of a rotary cylindrical screen, a casing in which said screen is partly enclosed, said casing having an inlet opening in one side thereof, a stationary air conduit extending into said screen for receiving the air flowing through the screen and discharging it from the condenser, and a tapered opening in the side of said conduit within the screen, the small end of said opening being located toward the discharge end of the conduit, and the width of said opening increasing toward the opposite end of the conduit.

4. In a condenser, the combination of a rotary cylindrical screen, a casing in which said screen is partly enclosed, said casing having an inlet opening in one side thereof, rolls on which the opposite ends of said screen near the periphery thereof are mounted to support the screen for rotation, a stationary air conduit in said screen arranged to receive the air flowing through the screen and discharge it from the condenser, and stationary dampers associated with the screen and substantially confining the suction caused by the flow of air through the screen to a portion only of the screen surface.

5. In a condenser, the combination of a rotary cylindrical screen, a casing in which said screen is partly enclosed, said casing having an inlet opening in one side thereof, a press roll at the fibre discharging side of the casing, means supporting said roll for swinging movement under the influence of gravity to press the fibre carried by the screen against the screen, a stripper roll mounted closely adjacent to the press roll, and means for driving said rolls at different peripheral speeds.

6. In a condenser, the combination of a rotary cylindrical screen, a casing in which said screen is partly enclosed, said casing having an inlet opening in one side thereof, a press roll at the fibre discharging side of the casing, means supporting said roll for swinging movement to press the fibre carried by the screen against the screen, and dampers for substantially closing the space between said press roll and said casing and between the screen and said conduit.

7. In a condenser, the combination of a rotary cylindrical screen including flanged rings supporting the opposite ends of the screening surface rolls supporting said rings and on which the flanges of said rings run, a casing partly enclosing said screen and supporting said rolls, said casing including plates fitting closely against the flanges of said rings but with a clearance between them, air holes through said plates for admitting

air to the space between said rings and plates, and means for revolving said screen.

8. In a condenser, the combination of a rotary cylindrical screen, a casing in which said screen is partly enclosed, rolls supporting said screen for rotation, said casing including plates fitting closely against the op-

posite ends of the screen but with a clearance space between them, air holes in said casing for admitting air to the space between said plates and the ends of the screen, and means for revolving said screen.

ROBERT S. CURLEY.
